ROOFING

Albert C. Fischer, Chicago, Ill., assignor to The
Philip Carey Manufacturing Company, a cor-
poration of Ohio

Application November 12, 1928, Serial No. 318,791

8 Claims. (Cl. 168—6)

This invention relates to roof coverings, and aims to provide a novel and improved structure in which shingle elements are secured between spaced supporting strips and conjoined into a composite covering of attractive design and appearance and capped with a ridge strip.

The invention consists in the features, combinations and arrangements, hereinafter described or claimed, for carrying out the above stated object and such other objects as will hereinafter appear.

In the drawings,

Figures 1, 2, 3, 6 and 7 are perspective views of various modifications of a ridge strip;

Figures 4 and 5 are perspective views of supporting strips to which roofing elements are attached;

Figures 8-11 inclusive, are detail views of the roofing elements and supporting strips assembled;

Figures 12-14 inclusive are modified forms of shingle elements adapted to be employed with the supporting strips;

Figure 15 is a perspective view of a section of roof embodying the present invention; and

Figure 16 is a cross sectional view of Figure 15.

Referring particularly to the drawings, 2 represents supporting strips which are formed to receive the edges of roofing elements 3 and support them in place. These supporting strips are preferably extruded or otherwise formed from a mass of bituminous material and linear fibers homogeneously mixed together, and comprise a base 4, a head 5, between which is a web or neck portion 6. In order to make a tight joint, a layer of adhesive 7 is advantageously distributed on the sides of the web, thereby forming a seal.

The shingle elements may be constructed of any material but are preferably of a rigid material, such as, slate, metal, asbestos-cement, and the like, especially when they are unsupported between the supporting strips, (Figs. 10 and 11). However, these elements may be of accurate shape, as shown by numeral 8, and laid with the convex face seated on the bases of adjacently laid supporting strips, thereby supporting them throughout their entire area (Figs. 8 and 9). The shingle elements are laid between the supporting strips in end to end relation, being in the form of individual shingles or in strips marked transversely at intervals 9 to simulate individual shingles.

Figs. 12, 13 and 14 illustrate other modifications of roofing elements which may be employed

between the supporting strips to provide various other designs. The ends of the elements are cut irregularly and the body marked at 10, either similar or dissimilar to one or both ends of the element.

Figs. 1, 2, 3, 6 and 7 illustrate modifications of ridge strips for capping roofing after it has been laid on a roofing deck, all of which are preferably formed from a mass of bituminous and fibrous material homogeneously mixed together. Strip 11 in Fig. 1 diverges from an apex into sides 12 and 13, and is coated on its exposed surfaces with granular material partially embedded therein. Strip 14 is substantially the same as 11 but has a bead 15 projecting from the apex to make it more pronounced. Numeral 16 represents a strip of arcuate formation, and in Figs. 6 and 7 these strips are marked transversely with grooves or the like 17.

Obviously the invention is not limited to the details of the illustrative embodiments all of which may be variously modified. Moreover, it is not indispensable that all features of the invention be used conjointly as certain features may be employed to advantage in various different combinations and sub-combinations.

Having described my invention I claim:

1. A roofing structure comprising a series of supporting strips of bituminous composition, each of which is provided with a base, head and web portion, shingle elements fitted against the web of the supporting strips, and a sealing strip applied to the edges of the roofing elements.

2. A roofing structure comprising a series of spaced supporting strips of bituminous composition, each of which is provided with a base, head, and web portion, and shingle elements fitted between the supporting strips and in contact with the entire top surface of the bases of said strips.

3. A roofing structure comprising a series of spaced supporting strips of bituminous composition, each of which is provided with a head, web and base portion, and shingle elements of arcuate formation fitted between the supporting strips with the convex faces in contact with the bases of adjacent strips.

4. A roof structure comprising a roof covering having a series of spaced supporting strips of bituminous composition and shingle elements arranged between the strips, and a ridge strip for capping the covering along the ridge of the roof.

5. A roof structure comprising a roof covering having a series of spaced supporting strips

and shingle elements arranged between and adhesively secured to the strips, and a preformed ridge strip of fiberized bituminous material for capping the covering along the ridge of the roof.

5 6. A roof structure comprising a roof covering having a series of spaced supporting strips with shingle elements arranged therebetween in parallel rows, and preformed ridge strips of fiberized bituminous material for capping the covering at the ridge of the roof.

10 7. A roofing structure comprising a series of spaced supporting strips of waterproof, conform-

able, plastic composition, each of which is provided with a web and head portion, and shingle elements fitted against the web beneath the head of the supporting strips.

8. An edging for roofing comprising a strip formed from a homogeneous mixture of fibrated bituminous material having a face portion adapted to abut against shingle elements and another portion adapted to be exposed to the weather, and a granular surfacing material partially embedded in the weather exposed portion.

10 ALBERT C. FISCHER.
